Primary Examiner — John Windmuller(74) *Attorney, Agent, or Firm* — Crestron Electronics Inc.(57) **CLAIM**

The ornamental design for a hand-held remote control, as shown and described.

DESCRIPTION

FIG. 1 shows a front perspective view of hand-held remote control.

FIG. 2 shows a rear perspective view of a hand-held remote control.

FIG. 3 shows a top plan view of a hand-held remote control; and,

FIG. 4 shows a right side elevation view of a hand-held remote control.

The broken lines in the figures depict a portion of the remote control that forms no part of the claimed design.
